ATTORNEY

UNITED STATES PATENT OFFICE.

GEORGE F. JOHNSON, OF AURORA, ILLINOIS.

STEM WINDING AND SETTING WATCH.

SPECIFICATION forming part of Letters Patent No. 406,513, dated July 9, 1889.

Application filed September 12, 1887. Serial No. 249,488. (No model.)

To all whom it may concern:

Be it known that I, GEORGE F. JOHNSON, a citizen of the United States, residing at Aurora, in the county of Kane and State of Illinois, have invented certain new and useful Improvements in Stem-Winding and Stem-Setting Watches, of which the following is a full, clear, and concise description.

This invention relates to that class of stem-winding and stem-setting watches in which the setting mechanism is thrown into engagement with the dial-wheels by pulling out the crown-piece and attached stem-key to a distance limited by a device within the watch-case. Other devices are used for the accomplishment of this purpose differing in various details of construction, but more essentially in the position which the stem-driven train assumes when the watch-movement is detached from the case. In one class of pendant-setting watches the stem-driven train stands in engagement with the dial-wheels, except when the watch is in the case. In a second class the said train stands in engagement with the winding-arbor. The first arrangement is disadvantageous from the fact that it interferes with the running of the watch when out of the case. An arrangement for obviating the second objection is shown in Letters Patent to C. P. Corliss, No. 325,506. My device, as hereinafter described, accomplishes the disengagement of the stem-driven train from the dial-wheels when the movement is out of the case, and is an improvement on the devices heretofore used, as it accomplishes the purpose designed without requiring the use of any auxiliary piece.

The construction of my device will be understood by referring to the accompanying drawings, forming part of this specification, in which similar letters indicate corresponding parts in the different figures.

Figure 1 represents a face view of a watch-movement with dial removed, showing the stem winding and setting parts in position for winding as they appear when in a case, having a crown-piece and attached stem-key (not shown) pushed in to its limit. This is the normal position of the winding and setting parts as the watch is carried in the case. Fig. 2 is a similar view of the face of a watch,

showing stem winding and setting parts in position for setting as they appear in the case, with the crown-piece pulled out to its limit. Fig. 3 is a similar view of face of watch, showing the position which the winding and setting parts assume when the watch-movement is out of the case and the parts are free from the limiting and restraining effect of the stem-key. Fig. 4 is a reverse view of Fig. 3, and shows, in connection with the other figures, how the movement of the stem-key operates to shift the winding and setting train.

In the drawings, A is the pillar-plate of the watch, upon which the winding and setting mechanism is mounted.

B is a movable yoke adapted to swing concentrically to the spur and bevel geared wheel C. The wheel C is meshed with a bevel-pinion P, which is actuated by a rotatable and longitudinally movable stem-key with attached crown or finger piece, (not shown,) forming part of the watch-case. This stem-key is limited in its longitudinal movement by an arrangement in common use in the cases adapted to Waltham and Elgin pendant-setting watches. The yoke B carries at opposite ends wheels D and E, one of which D meshes into the ratchet I, connected with the winding or barrel arbor N, and effects the winding. The other E meshes with the minute-wheel F, and through it communicates motion to the cannon - pinion J and effects the setting.

G is a locking-lever with attached pin e, extending through an opening in the watch-plate A and adapted to receive impulse from the lever h, pivoted upon the reverse side of the watch-plate, as shown in Fig. 4. The lever h is acted upon by a stem-key through the medium of a pin m, sliding longitudinally in a central hole in the bevel-pinion P, Fig. 4.

The locking-lever G is actuated by a spring K in a direction opposite to the impulse received from lever h. The pressure of the spring when the restraint of the lever h is removed, by pulling out the stem-key, causes the lever G to swing into contact with the projection 2 of the yoke B, thus throwing it into mesh with the minute-wheel F, (the position shown in Fig. 2,) for setting. When the stem-key is pushed in, the lever h, acting upon

the pin *e*, pushes the lever *G* from its engagement with the yoke *B*, which is then thrown into engagement with the ratchet *I*, when the parts are in the position (shown in Fig. 1) for winding.

Thus far, although my device differs in details of construction from others heretofore made and in use, it is somewhat similar in operation.

My improvement, which I claim, can best be understood by reference to Fig. 3, and consists in so constructing and arranging the parts as to cause or permit the stem-driven train to assume a neutral position, in which it is neither engaged with dial-wheels or winding-arbor when the watch-movement is out of the case. In this device it is effected by making the lever *G* capable of sufficient movement, when released from the restraint of the stem-key, to pass beyond the point 2 of yoke *B* and rest upon the inclined portion 3 of the same, the movement of the lever *G* being limited by the pin *e* striking the side of the opening in the watch-plate, or by other suitable means. The resting portion of lever *G* and the incline 3 are so adjusted to each other as to permit the yoke *B*, by the pressure of the spring *M*, to be thrown out of engagement with the dial-wheels without swinging far enough to engage with the ratchet-wheel *I*. This is the normal position of the winding and setting train when the watch is out of the case. The watch can, however, be wound or set when out of the case by the use

of an ordinary bench-key, giving sufficient end pressure upon pin *m* to force the parts into proper position.

I do not wish to be limited to the exact configuration of the point of the lever *G* and projection 2 of yoke *B*, shown in the drawings, as the reverse arrangement in which the inclines should be upon the locking-lever instead of the yoke and made to act upon a point of the yoke or upon a pin therein would be a practical equivalent. Instead of making both inclines upon either piece one incline could be made upon each.

Having thus described my invention, I claim as new and desire to secure by Letters Patent—

As an improvement in stem-winding and stem-setting watches, the lever *h*, actuated by the end-thrust of the stem-key, in combination with the lock-lever *G* and the swinging yoke *B*, said lock-lever and yoke being so formed at the point of their contact as to cause the yoke with its attached wheels to be locked in engagement with the dial-wheels when the lock-lever is restrained in its movements to a certain limit, but will permit the same to be automatically disengaged therefrom when the lock-lever is allowed additional movement, as when the watch is removed from the case, all substantially as shown and described.

GEORGE F. JOHNSON.
